SAFETY LOCK FOR VEHICLE DOORS

James N. Bethune, Arcadia, Calif.

Application July 1, 1949, Serial No. 102,529

3 Claims. (Cl. 70—181)

1

This invention relates to and has for an object the provision of a novel, efficient and simple safety lock for automobile doors by means of which, when employed in connection with conventional door locks, the doors of automobiles may not be accidentally or designedly opened from the inside, as by children confined in the rear part of an automobile, or unauthorizedly from the outside.

In the consideration of my invention, it may be understood that modern sedan automobiles of the four-door type are usually provided with buttons on the window ledges of the doors which are either depressible or liftable for locking the doors against opening from the outside and reversibly operable for rendering the doors openable by movement of the internal or external door handles. In some cases, the handles and door latches are so connected that the internal handles when moved in a door opening direction will unlock the doors while the external handles are ineffective for such purpose.

In all cases, the doors may be readily unlocked from the inside by movement of the handles or latch buttons and because of this fact children, when confined in the rear part of the car, are prone to tamper with the door handles and thereby either accidentally or designedly open a door, perhaps while the car is in motion, resulting in frequent serious injury.

It is, therefore, an object of this invention to provide a safety lock which is equally applicable to and in connection with different forms of door locks, latches and handles for preventing accidental or unauthorized opening of the doors of cars and without changing or impairing the locking and latching means provided on cars of modern design.

With the aforesaid and other objects in view, as will hereinafter appear, I have shown a preferred form of locking mechanism embodying my improvements in the annexed drawing, in which:

Fig. 1 is an elevational view of a typical automobile door locking mechanism with my auxiliary lock operatively applied thereto;

Fig. 2 is an enlarged sectional elevation of my latch arranged to lock when in uppermost position;

Fig. 3 is a section plan of the same on line 3—3 of Fig. 2;

Fig. 4 is a side elevational view of a special key for locking and unlocking my auxiliary lock;

Fig. 5 is a bottom view of the key as seen in the plane of line 5—5 of Fig. 4;

Fig. 6 is a sectional elevation of a modified form

2

of mechanism arranged to be depressed to its lowermost position for locking a door;

Fig. 7 is a sectional plan of the same on line 7—7 of Fig. 6.

Referring first to Fig. 1, it will be noted that I have shown a typical modern door lock assembly generally represented at L and mounted on a door D below the window ledge D'. While the details of unit L are not specifically important to my invention, it is well to understand that said unit includes a suitable base 1 on which a rotatable locking member 2 is mounted at the leading edge 3 of door D and is adapted for operation as by means of an actuator 4 pivoted at 5' on base 1 and connected as by means of elements 5 to member 2. Actuator 4 is connected by a bar 6 to the internal door handle (not shown) and also with my auxiliary lock L' through the typical rod 7 of unit L. Rod 7 has a portion 8 at its lower end which slides in an inclined slot 9 of a fixed plate 10 of unit L and is adapted to selectively seat in a peripheral groove 11 of actuator 4. Thus, when rod 7 is pulled upwardly, its portion 8 will disengage groove 11 and permit rotation of actuator 4 when the door handles are properly turned. When, however, rod 7 is thrust downwardly, its part 8 seats in groove 11 and prevents rotation of actuator 4 and member 2, thereby preventing the opening of door D.

In lieu of the usual button on the upper end of rod 7 above the door ledge D', I provide the auxiliary safety locking unit L' which operates and controls the unit L in the same manner as when the usual operating button (not shown) is fixed to rod 7. In addition, however, unit L' includes relatively fixed and movable locking members 15 and 16 enclosed in a suitable housing 17 as shown in Figs. 6 and 7, or corresponding members 15', 16' and 17', as shown in Figs. 2 and 3.

The form of unit shown in Figs. 6 and 7 has the housing 17 of inverted cup shape and a chamber 18 into the bottom of which the upright body 19 of member 15 telescopically fits and a closed upper end 20. Member 15 has a bottom flange 21 adapted to overlie door ledge D' and housing 17 has a larger flange 22 recessed to receive and overlying flange 21 of member 15. Screws 23 extend through flanges 21 and 22 and into door ledge D' and serve to firmly but detachably hold unit L' in position on door D. Member 15 is axially bored at 24 to receive the upwardly extended portion of rod 7 and the upper end portion 25 of rod 7 is threaded to detachably receive 55 and support the movable locking member 16.

Member 16 is normally urged upwardly to either locking or unlocking position, as the case may be, by means of a spring 26 in chamber 18 and compressed between member 15 and an annular flange 27 at the top of member 16. As shown in Fig. 7, member 15 has a plurality of alternating inwardly extended tongues 28 and grooves 29 extended entirely therethrough and a shallow recess 30 at the bottom thereof while member 16 has correspondingly formed tongues 31 matching grooves 29, and spaces 32 matching tongues 28.

Thus, when the tongues 31 are aligned with grooves 29, the member 16 may be slidably moved in body 19 of member 15 to the extreme positions where they will either overlie or underlie body 19 and when slightly rotated at either extreme position, will be held against axial movement in either locking or unlocking positions and, of course, will similarly hold rod 7 either in or out of engagement with actuator 4, as may be desired.

The modified form of unit L', of Fig. 2, is substantially similar to that of Fig. 6 only in the forms of the number 16' and housing 17'. The housing has a smaller bore 18' than chamber 18 of the unit of Fig. 6 and member 16' is internally bored at 16'a to receive a spring 26'. The housing 17' and member 15' have flanges 22' and 21', respectively, through which screws 23' extend for attaching the unit to door ledge D'. Member 16' has tongues 31' and grooves 29' are formed in member 15' in which the tongues 31' are slideable into and upwardly from the recesses 30' at the bottom of the unit.

In each form of unit L', the member 16 or 16' has a short upright extension 33 within an opening 34 in the top of the housing 17 or 17' with a transversely extended pin 35 projecting at opposite ends therefrom for receiving a special type of key K, as shown in Figs. 4 and 5.

Said key has a wing head 36 and a cylindrical shank 37 which is bored at 38 to receive extension 33 and diametrically slotted at 39 to receive the extended portions of pin 35 when shank 37 is inserted in opening 34 of the housing.

Hence, the key K is effective for locking the member 16 or 16' in either extreme position thereof for correspondingly setting the actuator 4 in locked or unlocked position, as may be desired. As the key is inserted in opening 34 of the housing with bore 38 over extension 33 and pin 35 in slots 39, the member 16 or 16' may be rotated on rod 7 sufficiently to register its tongues 31 or 31' with the grooves 29 or 29' of member 15 or 15' and then by applying pressure to the key, the member 16 or 16' may be depressed together with rod 7 to an extent whereat the tongues 31 or 31' will be in the recess 30 or 30' and by again turning the key and member 16 or 16' slightly, the tongues 31 or 31' thereof will underlie the body 19 of member 15 or 15'.

It is preferable to normally maintain unit L' in actuator locking position, whether the member 16 or 16' be downmost or uppermost in position. Hence, in such case, it is necessary to use key K for unlocking the actuator as well as for locking the same.

It will be apparent that even though members 16 and 15, or their counterparts 16' and 15', are arranged in registration for relatively slideable movement against the tension of spring 26 or 26', it is still necessary to depress or extend the member 16 or 16' by key K.

As shown in Figs. 2 and 6, the members 16 and 16' are constantly urged upwardly, but it is quite

apparent that, for example, if spring 26 in Fig. 6 were a tension spring instead of a compression spring and its uppermost coil were suitably attached to flange 27 of member 16 and the lowermost coil thereof attached to member 15, said spring would pull member 16 downwardly to locking plane at the bottom of member 15. When spring 26 is constituted as a tension spring, the slot 39 in key K should be formed as a bayonet slot and to such end may have a right angular extension 40 (Fig. 4) so as to engage pin 35 and lift member 16 against the tension of its spring to the unlocking plane at the top of member 15.

15 The arrangement of the locking members 15 and 16 in housing 17, or their counterparts, as otherwise shown, is such that the member 16 can not be rotated or depressed accidentally and even with improvised implements, the rotation and depression or extension would be difficult and due to such facts, full safety to children riding in the rear compartment of a car is provided.

20 Of course, the position of rod 7 influences the position of the actuator 4 which, in turn, either holds the door latch 2 locked or unlocked.

25 Thus, I have provided a novel, simple and efficient auxiliary safety locking mechanism particularly adapted for locking car doors against accidental or unauthorized opening of a door and is readily applicable to locking mechanisms of different types but equal effect and which will occupy but slightly more, if any, space than the conventional push or pull button types of manually operable locks.

30 35 What I claim is:

1. A locking mechanism comprising: a housing, a stationary locking member therein formed with concentric tongues and grooves; a coaxial movable locking member formed with tongues and grooves complementary with those of the stationary member whereby said movable member may be moved through the stationary member to locking and unlocking positions at opposite ends of the stationary member; and means 40 45 borne by the movable member for receiving a key whereby the movable member may be rotated into and from positions of registration with and for movement through the stationary member when actuated by said key for lockingly engaging the stationary member, said locking members being arranged to coaxially embrace an axially movable lockable member to which the movable member is adapted to be attached for locking the lockable member against movement in a given direction.

50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

normally urging the movable locking member to locked position.

3. A locking mechanism comprising: a housing, a stationary locking member therein formed with concentric tongues and grooves; a coaxial movable locking member formed with tongues and grooves complementary with those of the stationary member whereby said movable member may be moved through the stationary member to locking and unlocking positions at opposite ends of the stationary member; means borne by the movable member for receiving a key whereby the movable member may be rotated into and from positions of registration with and for movement through the stationary member when actuated by said key for lockingly engaging the stationary member, said locking members being arranged to coaxially embrace an axially movable lockable member to which the movable member is adapted to be attached for locking the lockable member against movement in a given direction; spring means between said locking members normally

urging the movable locking member to normally locked position; said housing enclosing all of said elements against access except by means of an operating key.
